MERCURY BOILER

Robert J. Carpenter, Scotia, N. Y., assignor to
General Electric Company, a corporation of
New York

Application August 17, 1938, Serial No. 225,475

5 Claims. (Cl. 122—235)

The present invention relates to mercury boilers or generally to elastic fluid generators including a drum located inside the boiler and subject to heat from the combustion and convection spaces during operation. Such boilers usually have a plurality of heating elements located in the combustion and convection spaces and arranged to receive liquid from the drum, and to discharge mixture of liquid and vapor or elastic fluid to the drum. In cases in which the drum is of considerable length with its axis horizontally disposed, it becomes important to reduce the axial or cross flow of liquid inside the drum, especially in the case of mercury boilers because there the axial flow inside the drum may cause considerable level differences in the drum due to the high flow resistance of mercury liquid.

The object of my invention is to provide an improved construction and arrangement of elastic fluid generators, particularly of mercury boilers whereby the aforementioned difficulties are substantially eliminated.

For a consideration of what I believe to be novel and my invention, attention is directed to the following description and the claims appended thereto in connection with the accompanying drawing.

In the drawing, Fig. 1 illustrates a sectional view partly broken away of a mercury boiler embodying my invention, and Fig. 2 is a section taken along line 2—2 of Fig. 1.

The arrangement comprises a casing formed by walls 10 and 11 which have adjacent portions connected by a sliding joint 12 to permit relative expansion of the walls during operation. The casing forms a combustion chamber 13. A cylindrical drum 14 is horizontally disposed in an intermediate portion of the combustion chamber projecting through the rear and front walls of the casing and dividing the combustion chamber into a primary combustion space below the drum and a secondary combustion space above the drum. Pairs of horizontal headers 15 and 16 are connected to each side of the drum 14 near the ends thereof. The rear wall of the combustion space below the drum is lined with heating tubes 17 connected at their upper ends to the headers 15, 16 and at their lower ends to headers 18 to which mercury liquid is supplied from the drum by means including down-tubes 20. During operation, mercury liquid is conducted from the drum 14 through the down-tubes 20 and the headers 18, whence it flows through the up-tubes 17 and is heated therein,

the mixture of mercury liquid and vapor thus formed being discharged into the headers 15, 16 and the drum 14. The side walls of the combustion space are lined with heating tubes 21 and 22. The lower ends of the heating tubes 21 are connected to headers 23, which latter are connected to the aforementioned down-tubes 20 to receive mercury therefrom. The upper ends of the tubes 21 which constitute up-tubes with regard to the flow of mercury therein are bent inwardly and arranged in groups of twisted or roped tubes 24 connected to the drum 14 to discharge the mixture of mercury liquid and vapor formed during operation into the latter. The tubes 22 are connected at their upper ends to mercury liquid supply means including headers 25 to receive mercury liquid to be heated from the latter. With regard to the downward direction of the flow through the tubes 22 they may be termed down-tubes. The lower ends of the tubes 22 are bent upwardly and connected to ropes of tubes 26 located above the ropes 24, preferably in staggered relation to the latter, to act as slag screens.

The ropes of tubes 26 extend to a level near the drum and are connected to the lower ends 25 of walls of inclined tubes 27, 28 located in the secondary combustion space and extending along the drum 14. The secondary combustion space also contains down-tubes 29 lining the rear walls and connected at the lower ends to the headers 30, 31. The side walls of the secondary combustion space are lined with down-tubes 30 which have lower end portions 31 curved inwardly and connected to discharge heated mercury into the drum 14. A more detailed description of the heating elements and the general arrangement of the boiler may be found in the application of B. P. Coulson, Jr., filed on the same date and assigned to the same assignee as the present application, Serial Number 225,464.

In order to reduce the amount of mercury liquid necessary for operating the boiler and to effect good separation of mercury liquid and vapor inside the drum, it is important to maintain a low, substantially uniform mercury level inside the drum. To this end the mercury liquid is discharged from the drum in accordance with my invention by means of a plurality of spaced, substantially vertical conduits or conduit branches 32 connected to the bottom of the drum and discharging the mercury liquid into two conduits 33 and 34 which have outer ends connected to the down-tubes or conduits 20. Each of the conduits 33 and 34 has a plurality of sections 35, 36 with a diameter increasing in

the direction of flow, this direction being indicated by arrows (Fig. 2). The conduits and conduit portions 32 to 36 are located below the drum and enclosed by a horizontal channel or casing 5 37 made of heat insulating and heat resistant material. The casing is substantially triangularly shaped with the point of the triangle pointing downward and the base formed by heat insulating material covering the bottom of the 10 drum 14, thus offering a minimum resistance to the flow of combustion gases from the primary to the secondary combustion space. The casing 37 projects through the entire boiler and is opened in the front and rear as shown in Fig. 15 2 so that the down-tubes may be readily inspected. Thus, the down-tubes and their connections to the bottom of the drum 14 are completely protected from the radiant heat in the 20 primary combustion space. The plurality of connecting conduits 32 and the increasing diameters of the sections 35, 36 assure uniform discharge of mercury liquid from the different portions of the drum whereby a substantially uniform level is maintained inside the drum and 25 cross-flow, that is, flow of liquid mercury in the direction of the axis of the drum is substantially eliminated. The outer surface of the casing 37 is covered or lined with heating tubes having lower portions connected to the ropes of tubes 30 24 and upper end portions connected to discharge heated mercury into the drum.

The mixture of mercury liquid and vapor discharged into the drum from the various heating elements is separated inside the drum. The separating device includes a cylindrical segment 38 35 forming together with the upper portion of the drum an annular channel 39 into which the heated mixture of mercury liquid and vapor is discharged during operation. The mixture flows 40 circumferentially along the channel into a mercury pool 40 formed on the bottom of the drum, the liquid mercury being recirculated through the down-tubes and the mercury vapor is discharged through a plurality of vapor discharge conduits 45 41 which are connected to the segment 38 to communicate directly with the space inside the cylindrical segment. The provision of a plurality of discharge conduits 41, in the present instance four, assures uniform discharge of vapor from 50 the various portions of the drum and also reduces disturbances of the pool which otherwise might occur. The vapor discharge conduits 41 are enclosed by a housing or casing 42 made of heat insulating and heat-resistant material. The 55 walls of this housing converge upwardly to offer minimum resistance to the flow of combustion gases through the secondary combustion chamber. The housing 42 is open at one end, as shown in Fig. 2. The outer surfaces of the housing 60 walls are lined by the aforementioned walls of heating tubes 27, 28 to protect the housing from heat.

What I claim as new and desire to secure by Letters Patent of the United States is:

65 1. Elastic fluid generator comprising a casing forming combustion and convection spaces, a drum located at least partly within said spaces, heating elements disposed within said spaces and connected to discharge hot fluid to the drum, 70 and means for conducting liquid from the drum

to said heating elements, said means comprising a conduit having an upper horizontal portion located in the casing below and in proximity to the drum with a plurality of branches connected to spaced portions of the bottom of the drum and a wall of heat-insulating material below the horizontal portion. 5

2. In an elastic fluid generator, the combination of a horizontally disposed drum, and means for discharging liquid from the drum comprising 10 a conduit located below the drum and having a plurality of branches connected to separate portions along the bottom of the drum, the conduit having a diameter increasing in the direction of flow of liquid therethrough in order to effect uniform 15 discharge of liquid from the various portions of the drum and substantially to eliminate cross-flow within the drum.

3. A mercury boiler comprising walls forming a combustion chamber, a drum supported on the 20 walls and projecting into the chamber, a horizontal heat-insulated channel formed below the drum and communicating with the atmosphere, heating elements located in the chamber and having discharge ends connected to the drum, 25 and means for conducting liquid from the drum to the inlets of the heating elements comprising a conduit having an upper portion substantially horizontally disposed in the channel with branches connected to spaced bottom portions 30 of the drum to effect complete mixing of liquid from several portions of the drum before the liquid is admitted to any of the heating elements.

4. A mercury boiler comprising walls forming a combustion chamber, a drum supported on the 35 walls and projecting into the chamber, heating elements located in the chamber and having discharge ends connected to the drum, means for conducting liquid from the drum to the inlets of the heating elements comprising a conduit 40 having a portion substantially horizontally disposed below the drum with branches connected to spaced bottom portions of the drum, said conduit portion having a diameter increasing in the direction of flow of liquid therethrough, and 45 means protecting said conduit from the heat in the combustion chamber comprising a casing partly formed by the drum and enclosing the conduit portion with its branches.

5. A mercury boiler comprising a casing forming a combustion chamber, a drum supported on the casing and projecting through the chamber and dividing it into a primary combustion space below the drum and a secondary combustion space above the drum, heat insulating material 55 covering the drum within the chamber, means including a plurality of conduits connected to axially spaced bottom portions of the drum for uniformly discharging mercury liquid from the various portions of the drum, and means for protecting said conduits from the heat in the chamber comprising a triangularly-shaped casing with a base formed by the drum and pointing downwardly thus reducing the resistance of the flow of combustion gases from the primary to the secondary chamber, said protecting casing extending horizontally through the boiler casing and being open at its ends to permit inspection of the conduits during operation. 60 65
